UNITED STATES PATENT OFFICE

153,863

DESIGN FOR A COMBINED PORTABLE MOTION-PICTURE PROJECTOR APPARATUS AND CARRYING CASE THEREFOR

William Charles De Vry, Chicago, Ill., assignor to De Vry Corporation, Chicago, Ill., a corporation of Illinois

Application November 19, 1947, Serial No. 142,650

Term of patent 3½ years

(Cl. D61—1)

To all whom it may concern:

Be it known that I, William C. De Vry, a citizen of the United States and a resident of Chicago, in the county of Cook and State of Illinois, have invented a new, original, and ornamental Design for a Combined Portable Motion-Picture Projector Apparatus and Carrying Case Therefor, of which the following is a specification, reference being had to the accompanying drawing, forming a part thereof, and in which:

Fig. 1 is a perspective view of a combined portable motion picture projector apparatus and carrying case therefor, in closed condition, showing my new design;

Fig. 2 is a perspective view similar to Fig. 1, but with the parts in open condition; and

Fig. 3 is a perspective view of the side opposite to that shown in Fig. 2.

I claim:

The ornamental design for a combined portable motion-picture projector apparatus and carrying case therefor, as shown and described.

WILLIAM CHARLES DE VRY.
